(57) **CLAIM**

The ornamental design for a lawn trimmer as shown and described.

DESCRIPTION

FIG. 1 is a perspective view of a lawn trimmer showing our new design;

FIG. 2 is a front elevational view of the lawn trimmer of FIG. 1;

FIG. 3 is a rear elevational view of the lawn trimmer of FIG. 1;

FIG. 4 is a left side elevational view of the lawn trimmer of FIG. 1;

FIG. 5 is a right side elevational view of the lawn trimmer of FIG. 1;

FIG. 6 is a top plan view of the lawn trimmer of FIG. 1; and, FIG. 7 is a bottom plan view of the lawn trimmer of FIG. 1. The broken lines shown in the drawings depict portions of the lawn trimmer that form no part of the claimed design.

1 Claim, 4 Drawing Sheets
